United States Patent Office

Des. 193,490
Patented Aug. 28, 1962

193,490

OPTICAL COMPARATOR

Philip N. Welch, Main St., Chester, Vt., and Glenn A. Wheelock, 130 Summer St., Springfield, Vt.

Filed Aug. 17, 1961, Ser. No. 66,386

Term of patent 14 years

(Cl. D57—1)

FIG. 1.

FIG. 2.

FIG. 3

FIG. 4

FIG. 1 is a front perspective view of an optical comparator showing my new design;

FIG. 2 is a front elevational view thereof;

FIG. 3 is a side elevation view thereof taken from the right of FIG. 2; and

FIG. 4 is a rear elevation view.

We claim:

The ornamental design for an optical comparator, as shown.
